UNITED STATES PATENT OFFICE

2,536,762

DRIER

Kenneth E. McConaughay, West Lafayette, Ind.

Application August 2, 1944, Serial No. 547,668

8 Claims. (Cl. 34—135)

1

My invention relates to driers of the rotary drum type such as are commonly used in the drying of crushed stone or other aggregate intended for incorporation in a paving composition.

As heretofore made, such driers have usually been in the form of a generally cylindrical drum rotating about an axis inclined to the horizontal and provided interiorly with flights or vanes by which the material passing through the drum is lifted and caused to fall repeatedly through a stream of heated air passing through the drum. In order to provide for adequate drying, such drums must frequently be of great length; and as the result of their inclination to the horizontal, their inlet ends are located at such a distance above the ground that the operation of supplying aggregate to them requires special elevating equipment.

It is the object of my invention to produce a drier which will be more compact than the common form of drier, which requires no extra means for elevating aggregate to its inlet end, and which will operate to remove moisture from the aggregate quickly and efficiently.

In carrying out my invention, I employ a rotating drum having co-axial portions of widely differing diameters, each portion being provided with aggregate-elevating flights. The drum is mounted for rotation with its axis inclined downwardly from the larger-diameter portion of the drum. The open end of the larger-diameter portion of the drum is closed by a stationary plate provided near its bottom with openings for the admission of aggregate and heated air and near its top with an opening for the discharge of air. A burner or other suitable means supplies heated air to the larger-diameter portion of the drum through the air-inlet opening, while a second burner or other means supplies heated air to the discharge end of the smaller-diameter drum-portion. In the preferred form of the invention, an adjustable means is provided for regulating the rate at which aggregate is fed from the larger-diameter drum portion to the smaller-diameter drum portion.

The accompanying drawing illustrates my invention: Fig. 1 is a side elevation of the drier with portions of the drum broken away to illustrate the internal construction; Fig. 2 is an end elevation of the drum; and Fig. 3 is a fragmental plan view of the interior of the drum illustrating a means which may be employed to control the rate at which the material being dried is fed into the smaller drum-portion.

The drier-drum illustrated in the drawing com-

2

prises a large-diameter portion 10 and a small-diameter portion 11 joined by an annular end wall 12. The smaller-diameter portion 11 is provided with axially spaced supporting rings 13 received in the grooves of grooved rollers 14 rotatably mounted on a base frame 15. A sprocket 16 mounted on the drum-portion 11 is connected by a chain 17 to an electric motor 18 or other source of power by means of which the drum is rotated.

The drum-supporting rollers 14 are so arranged on the base frame 15 that the drum 10—11 is supported in a position with its axis extending downwardly from the larger-diameter portion 10 to the open end of the smaller-diameter portion 11. To aid in transmitting to the base frame the axial thrust resulting from this inclined position of the drum, the base frame may be provided with rotatably mounted rollers 20 engaging the outer surface of the annular wall 12.

Interiorly, the larger-diameter portion 10 of the drum is provided with an annular series of axially extending flights 21, while a similar annular series of flights 22 is provided within the smaller-diameter drum portion 11. As will be obvious, these flights operate when the drum is rotated to elevate the aggregate passing through the drum and to drop it across the drum.

To control the rate at which aggregate is fed from the drum portion 10 into the drum portion 11, the latter may be provided with a feed-scoop 25 which extends circumferentially of the smaller drum-portion and projects axially into the larger drum-portion 10. As shown, the scoop 25 is adjustable to vary the extent to which it projects into the drum portion 10, and hence to vary the amount of aggregate which the scoop intercepts at each drum-revolution. Such adjustment of the scoop is conveniently effected by securing it to the circumferential wall of the drum-portion 11 by bolts 26 which project outwardly through longitudinally extending slots 27 in the drum-wall.

The open end of the larger drum-portion 10 is covered by a stationary plate 30 supported in appropriate manner from the base frame 15. In one of the lower quadrants of the plate 30, there is provided an air-admission opening 31, and in the other lower quadrant there is an aggregate-admitting opening associated with a hopper 32 which projects outwardly from the plate 30. The hopper is conveniently so dimensioned and positioned that a dump-truck can discharge its load directly into it. Mounted outside the opening 31 and in general alignment therewith is a burner

33, which discharges into the drum-portion 10 through the opening 31, such burner being supported from the plate 30 or base frame 15. A second burner 34 is supported from the base frame 15 in a position to discharge into the open end of the small drum-portion 11.

Near its upper end, the plate 30 is provided with an air outlet opening 36 communicating with an exhaust stack 37. If desired, I may associate with the exhaust stack some means for inducing upward air flow therethrough, such means being shown in the drawing as a nozzle 38 projecting obliquely through the wall of the stack to discharge thereinto a flow-inducing jet of air or steam.

In operation, the burners 33 and 34 are ignited, the motor 18 is started to rotate the drum, and aggregate is supplied to the hopper 32. The aggregate so supplied enters the lower part of the large drum-portion 10, and is carried upwardly along one side thereof by the flights 21. As those flights successively reach an inclined position above the drum-axis, the aggregate resting upon them falls under the influence of gravity through the heated atmosphere created by the burner 33. The burner 33 is desirably mounted in such a position that its flame is not directed into the small-diameter drum-portion 11 where it would interfere with the air stream created therein by the burner 34. In other words, the flame is largely confined within the axially projected limits of the annular wall 12 so that it will impinge upon such wall rather than entering the smaller drum-portion 11. As a result, practically all of the hot products of combustion from the burner 33 and practically all of the air entering through the opening 31 passes generally upwardly through the larger-diameter drum-portion 10 to enter the exhaust opening 36 without traversing any portion of the small drum-portion 11.

At each revolution of the drum, some of the aggregate discharged by the flights 21 will fall into the small-diameter drum-portion, either directly or after interception, by the scoop 25 and will work under the influence of gravity through the small drum-portion 11. As it passes downwardly through such smaller drum-portion 11, the aggregate will be repeatedly lifted and dropped through the stream of air resulting from the presence of the burner 34.

The size and proportions of the drier will depend upon its desired capacity and upon the amount of moisture which it is desired to remove from the material being dried. Ordinarily, the chamber defined by the annular side wall of the larger-diameter drum-portion 10 and by the end wall 12 will have a diameter materially greater than its axial extent. The smaller-diameter drum-portion 11 desirably has a length equal to at least twice its diameter, and is preferably even longer. The diameter of the larger drum-portion 10 is such that it extends downwardly beyond the point at which it is convenient to load aggregate into it, and it is thus possible to have the drum-axis slope downwardly from the inlet end of the drum to the discharge and without the necessity of providing means for elevating aggregate into the discharge end.

In my drier, the wet aggregate entering the larger drum-portion comes into immediate contact with the heated air which enters the opening 31. Such air, coming directly from the burner 33, is both hotter and drier than it would be if it had previously been in contact with incompletely dried aggregate. Further, such air passes

rapidly through the drum-portion 10, as its general path is almost directly upward. As a result of these facts, the removal of moisture from the aggregate within the drum-portion 10 tends to induce air-flow axially through the smaller-diameter drum-portion 11, and thus increases the rate of air-flow and the drying action occurring in such drum-portion 11. In some instances, as where the aggregate is not too wet and it is desired that its temperature at discharge be not too high, the burner 34 at the discharge end of the drier may be eliminated. In such a case, there will be an induced flow of relatively cool air through the small-diameter drum-portion 10, and the aggregate therein will be both cooled and further dried.

I claim as my invention:

1. A drier for aggregate and the like, comprising a drum having intercommunicating portions of materially different diameter interconnected by an annular wall, means rotatably supporting said drum with its axis sloping downwardly from the portion of larger diameter, means for rotating the drum about its axis, a stationary plate closing the open end of the larger-diameter drum-portion, said plate being provided in its lower portion with openings for the admission of air and aggregate and in its upper portion with an air-outlet opening, means for supplying a stream of heated air through said air admission opening toward said annular wall, means for directing a second stream of heated air into the lower end of the smaller drum-portion, and flights on the interior of both drum-portions for elevating aggregate and causing it to fall through said air-streams as the drum is rotated.

2. A drier for aggregate and the like, comprising a first circumferentially continuous drum portion, axially spaced end walls therefor, a second circumferentially continuous drum-portion coaxial with said first drum portion, said second drum portion being of materially smaller diameter than said first portion and extending axially therefrom, means supporting said drum portions for rotation about an axis inclined downwardly from the large drum portion to the small drum portion, the lower of said end walls having a central opening providing communication between the two drum-portions, means for directing a stream of heated air into the lower part of said larger drum portion and toward the lower end wall beyond the periphery of said opening therein, the upper end wall substantially closing the upper end of the first drum portion and being provided with an aggregate-admitting opening and in its upper portion with an air-escape opening, means for directing a second stream of heated air into the lower end of the smaller drum-portion, means for rotating the drum portions about their common axis, and flights on the interior of both drum-portions for elevating and releasing aggregate.

3. A drier for aggregate and the like, comprising a first circumferentially continuous drum portion, axially spaced end walls therefor, a second circumferentially continuous drum-portion coaxial with said first drum portion, said second drum portion being of materially smaller diameter than said first portion and extending axially therefrom, means supporting said drum portions for rotation about an axis inclined downwardly from the large drum portion to the small drum portion, the lower of said end walls having a central opening providing communication between the two drum-portions, means for directing a

stream of heated air into the lower part of said larger drum portion and toward the lower end wall beyond the periphery of said opening therein, the upper end wall substantially closing the upper end of the first drum portion and being provided with an aggregate-admitting opening and in its upper portion with an air-escape opening, means for rotating the drum portions about their common axis, and flights on the interior of both drum-portions for elevating and releasing aggregate.

4. The invention set forth in claim 3 with the addition of a scoop extending circumferentially of the lower drum-portion and projecting therefrom into the upper drum-portion to intercept and direct into the lower drum-portion aggregate released by the flights in the upper drum-portion, said scoop being adjustable axially of the drum to vary the extent to which it projects into the upper portion thereof.

5. The invention set forth in claim 3 with the addition of a scoop extending circumferentially of the lower drum-portion and projecting therefrom into the upper drum-portion to intercept and direct into the lower drum-portion aggregate released by the flights in the upper drum-portion.

6. The invention set forth in claim 1 with the addition of a vertical stack connected to said air-outlet opening, and means associated with said stack for inducing an upward flow of air therethrough.

7. The invention set forth in claim 1 with the addition of a vertical stack connected to said air-outlet opening.

8. In a drier for aggregate and the like, a rotatable drum disposed on an inclined axis and having an annular side wall, axially spaced end walls defining in co-operation with said side wall a drying chamber having a diameter greater than its axial extent, said side wall being provided interiorly with flights for elevating and dropping aggregate as the drum rotates, the lower of said end walls being rigid with the drum and provided

with a central opening through which some of the aggregate dropped from said flights may escape, the upper of said end walls being stationary and being provided in its lower portion with an aggregate-admitting opening, said upper end wall also being provided with air-admission and air-outlet openings, and means for supplying heated air to said chamber through said air-admission opening, said air-admission opening being located in the lower portion and said air-outlet opening in the upper portion of said upper end wall whereby heated air will flow generally upwardly and diametrically through the drying chamber counter to the movement of aggregate dropped from said flights.
